the supply and delivery receptacle being therefore located at the same end of the machine where the envelopes can be conveniently handled.

5. What I claim is:—

1. In an envelop feeding mechanism, the combination of means for supporting a supply of envelopes, means to engage beneath the flap of an envelop and push said envelop into printing position, and means to engage an exterior edge of the envelop and pull said envelop away from printing position.
2. In an envelop feeding mechanism, the combination of means for supporting a supply of envelopes, fingers adapted to engage the flap of the first envelop in the supply and feed it forward to printing position, other fingers longer than the feeding fingers and movable conjointly therewith adapted to engage the envelop after the printing operation is completed and deliver it and move it away from printing position in a direction beneath the supply.
3. In an envelop feeding mechanism, the combination of means for supporting a supply of envelopes, a frame, means for oscillating the frame, fingers carried by the frame adapted to engage the flap of the first envelop in the supply and feed it forward to printing position, and other means carried by the frame to engage the envelop after the printing operation is completed and move it rearward away from printing position in a direction beneath the supply.
4. In an envelop feeding mechanism, the combination of means for supporting a supply of envelopes, a frame, means for oscillating the frame, fingers carried by the frame to engage the flap of the first envelop in the supply and feed it forward to printing position, delivery fingers carried by the frame and movable conjointly with the feeding fingers, said delivery fingers being longer than the feeding fingers and adapted to engage the envelop on the rearward movement of the frame, and means for holding the envelop in substantially fixed position to enable the feeding fingers to move out of operative engagement therewith before the delivery fingers engage the envelop.
5. In an envelop feeding mechanism, the combination of spring fingers for feeding the envelopes from a supply to printing position, and spring fingers conjointly movable with the feeding fingers but operable on the envelop independently of the feeding fingers to deliver the envelop after it is printed.
6. In an envelop feeding mechanism, the combination of spring fingers for feeding the envelopes from a supply to printing position, spring fingers conjointly movable with the feeding fingers but operable on the envelop independently of the feeding fingers to deliver the envelop after it is printed, and

means for holding the envelop in fixed position to enable the feeding fingers to move out of operative engagement therewith before the delivery fingers move into operative engagement therewith.

7. In an envelop feeding mechanism, the combination of spring fingers for feeding the envelopes from a supply to printing position, spring fingers conjointly movable with the feeding fingers but operable on the envelop independently of the feeding fingers to deliver the envelop after it is printed, means for holding the envelop in fixed position to enable the feeding fingers to move out of operative engagement therewith before the delivery fingers move into operative engagement therewith, and means for adjusting said holding fingers for envelopes of different widths.

8. In an envelop feeding mechanism, the combination of devices for feeding the envelopes from a supply to printing position, delivery devices conjointly movable with the feeding devices but operable on the envelop independently of the feeding devices, and a face plate on the machine for guiding the envelop and the feeding and delivery devices.

9. In an envelop feeding mechanism, the combination of means for engaging an envelop beneath the flap thereof and feeding said envelop flap edge foremost to printing position, and means for engaging said envelop at the flap edge exteriorly of the flap and removing said envelop flap edge last from printing position.

10. In an envelop feeding mechanism, the combination of a movable member, an envelop feeding device mounted thereon and adapted to engage an envelop beneath the flap thereof, and a delivery device mounted on said movable member to engage with the envelop after the feeding device has been released therefrom and remove said envelop from printing position.

11. In an envelop feeding mechanism, the combination of a movable member, a device carried thereby and adapted to engage beneath the flap of an envelop and feed said envelop to printing position, and a device carried by said member and adapted to engage the flap edge of said envelop and remove the envelop from printing position.

12. In an envelop feeding mechanism, the combination of an oscillatory member, an envelop feeding and an envelop removing device each mounted on said oscillatory member, and means for actuating said member whereby an envelop is fed flap edge foremost by said feeding means to printing position and subsequently removed flap edge rearmost from printing position.

13. In an envelop feeding mechanism, the combination of an oscillatory member, a spring finger carried thereby in position to
